US0D1112255S

(12) **United States Design Patent** (10) Patent No.: **US D1,112,255 S**
(45) Date of Patent: ** Feb. 10, 2026

(54) **DISPLAY SCREEN OR PORTION THEREOF
WITH A GRAPHICAL USER INTERFACE**

(71) Applicant: **SILVUS TECHNOLOGIES, INC.**,
Los Angeles, CA (US)

(72) Inventors: **Neema Daneshvar**, Los Angeles, CA
(US); **Ajit Warrier**, Los Angeles, CA
(US); **Chris Nersesyan**, Los Angeles,
CA (US); **Jimi Henderson**, La Mesa,
CA (US); **Weijun Zhu**, Walnut, CA
(US)

(73) Assignee: **SILVUS TECHNOLOGIES, INC.**,
Los Angeles, CA (US)

(**) Term: **15 Years**

(21) Appl. No.: **29/873,187**

(22) Filed: **Mar. 27, 2023**

Related U.S. Application Data

(62) Division of application No. 29/704,276, filed on Sep.
3, 2019, now Pat. No. Des. 982,021.

(51) **LOC (15) Cl.** **14-04**

(52) **U.S. Cl.**

USPC **D14/485**

CLAIM

The ornamental design for a display screen or portion thereof with a graphical user interface, as shown and described.

DESCRIPTION

The file of this patent contains at least one drawing/photograph executed in color. Copies of this patent with color drawing(s)/photograph(s) will be provided by the Office upon request and payment of necessary fee.

FIG. 1 is a front view of a display screen or portion thereof with graphical user interface in accordance with a first embodiment;

FIG. 2 is a front view of a display screen or portion thereof with graphical user interface in accordance with a second embodiment;

FIG. 3 is a front view of a display screen or portion thereof with graphical user interface in accordance with a third embodiment;

FIG. 4 is a front view of a display screen or portion thereof with graphical user interface in accordance with a fourth embodiment;

FIG. 5 is a front view of a display screen or portion thereof with graphical user interface in accordance with a fifth embodiment; and,

FIG. 6 is a front view of a display screen or portion thereof with graphical user interface in accordance with a sixth embodiment.

The broken lines, including those showing a display screen or portion thereof and those depicting portions of a graphical user interface, form no part of the claimed design. The ornamental design for a display screen or portion thereof with a graphical user interface, shown in any of FIGS. 1-6, may be within a graphical user interface, such as a radio network topology graphical user interface, of a computer. Shading represents areas of contrasting appearance and forms part of the claimed design.
